CONCENTRATOR

Wayne W. Blackburn, Clearwater, Fla.

Application March 4, 1953, Serial No. 340,345

4 Claims. (Cl. 209—1)

1

This invention relates to placer mining and more particularly to equipment for handling various types of earth in which are located various kinds of deposits, including gold and other precious metals.

Equipment heretofore employed not only has been bulky and unwieldy, but has been difficult to transport and use and has not afforded protection to the hands of the user.

It is an object of the invention to provide a simple, inexpensive kit consisting of the necessary parts, housed in a single casing, a portion of which, can be used for a camp stool, and in which kit the necessary tools may also be contained, as well as a kit which can be easily used for an extended period without material wear or injury to the fingers or hands of the operator.

Another object of the invention is to provide a kit of simple parts which can easily be cleaned and assembled for use.

Other objects and advantages will become apparent from the following description taken in conjunction with the accompanying drawing in which

Fig. 1 is a perspective of a concentrator and prospector's kit in accordance with the present invention;

Figs. 2 and 3, perspective views of the top and base portions of the kit respectively;

Fig. 4, a top plan view of the transversely curved perforated sieve;

Fig. 5, a top plan view of the grill or riffle;

Figs. 6 and 7 top plan and perspective views respectively of a pair of pans used for the collection of the deposits, and

Fig. 8 a plan view of tools used in connection with the kit.

Briefly stated, the invention comprises a concentrator or prospector's kit consisting of a top and a base adapted to be fastened together by means of a hasp, a staple and a lock and with a pair of handles, one for use in carrying the structure and the other in shifting or moving the top when it is used as a stool.

Hooks and eyes may be employed for connection of the parts at opposite corners of the top and base. When the top and base are separated and used the top is usually placed beside the base for convenience. A sieve or strainer is contained on the base and into which the soil of the pan is placed. This sieve has openings therein and an outwardly turned flange along the length of each side by means of which the sieve is supported on the base. A frame fills the base from side to side and end to end such frame consisting

2

of a plurality of longitudinal and transverse riffle bars so that when the soil passes through the sieve with the water, it can be received through these bars and held for a time.

5 The base is preferably provided with a reinforcing transverse end bar extending from side to side across the upper portion of its discharge end. This adds strength to the base, but leaves a relatively wide-open space beneath the same.

10 Pans of any desired size or shape as illustrated in Figs. 6 and 7 may be employed, such pans being relatively shallow and being adapted to be applied beneath the discharge end of the base. After a substantial deposit is accumulated between the riffle bars of the grill the frame is raised to discharge the major portion of such deposit. Tools 27, 28, 29 and 30, such as those shown in Fig. 8 may be employed for supplying the soil into a sieve, for breaking up rock or the like and for agitating the material in the sieve.

15 With continued reference to the drawing, the invention comprises a concentrator or prospector's kit having a substantially rectangular top 10 and a correspondingly shaped base 11 adapted to be fastened together by means of a hasp 12, a staple 13, and a lock 14.

The top substantially encloses the base and is provided with a handle 15 by which it may be carried. An additional handle 16 may be provided for assisting in moving the top when it is used as a seat or a stool.

20 The top can be placed on the ground like the position shown in Fig. 3, and used as a seat. It is preferably located beside the base when used as a seat so that the person using the kit may have ready access to the base.

In order to more securely fasten the base and top together, hooks 17 and eyes may be employed for connecting the parts at opposite corners of the top and base.

25 Within the base is located a sieve or strainer 19 into which soil to be panned is placed and over which water is caused to be washed so that the lighter constituents can be carried away and the heavier constituents retained along the floor of the base.

The sieve 19 has an outwardly disposed flange 20 along each side and by means of which it may be supported on the base. The sieve is provided 30 with openings 21 through which the water and panned earth drop into a frame covering the floor of the base from side to side and end to end, such frame being composed of longitudinal bars 22 and transverse bars 23. The transverse bars 23 have their ends offset so that a circuitous or

serpentine path of travel is provided from one end of the floor of the base to the other, such transverse bars being in contact with the floor of the base and the longitudinal bars being located upon the same.

When in use the device is preferably disposed in an inclined position with the discharge end at slightly lower than the opposite end of the base so that the water and the lighter constituents may readily pass from the discharge end of the device. Accordingly, the sieve has one end 19' closed and such closed end is in the lower position.

The base is preferably provided with a transverse end bar 24 connecting the sides across the upper portion of the discharge end thus adding strength but permitting free discharge from the device. As illustrated in Fig. 2 of the drawing, the transverse end bar 24 may be provided with interior shoulders 31 upon which the closed end of the sieve 20 is supported. Additionally, the base 11 may be provided with spaced supporting blocks 32 upon which the outermost slats 22 rest; thus the frame formed by the longitudinal bars 22 and transverse bars 23 is retained in proper position within the kit.

In the use of the device the heavier constituents which accumulate on the floor of the base may be discharged into one or more pans 25 or 26 of any desired size and shape as illustrated in Figs. 6 and 7. Such pans being preferably relatively shallow for convenience and being adapted to be placed beneath the discharge end of the base.

Tools such as a shovel 27, a hatchet 28, a hammer 29 and a fork 30, as illustrated in Fig. 8, may be employed during the use of the device. With these tools the soil may be placed into the sieve, the hatchet and hammer may be employed for breaking up deposits or the like, and the fork may be used for stirring or agitating the material in the sieve for separating the constituents so that the lighter may be washed away and the heavier and more valuable retained.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A prospector's kit comprising a hollow base, a top encasing said base, and adapted to be used as a stool, a curved material receiving sieve having openings therein and also having side portions adapted to rest upon said base, said sieve having a closure at one end, a frame corresponding in length and breadth to said base and comprising transverse bars and longitudinal bars

supported on said transverse bars, and with the latter alternately offset to provide a serpentine path between and around the ends of said transverse bars from one end of the base to the other,

5 said base having an opening at one end along its floor and portions extending inwardly from the sides and providing a central discharge way, means for fastening said top over said base to provide a compact package, and a handle on said top by means of which the kit may be carried.

2. A prospector's kit comprising a hollow base, a top encasing said base and adapted to be used as a stool, a curved material receiving sieve having openings therein and also having side portions adapted to rest upon said base, a frame corresponding in length and breadth to said base and comprising transverse bars and longitudinal bars

15 supported on said transverse bars, and with the latter alternately offset to provide a serpentine path between and around the ends of said transverse bars from one end of the base to the other, means for fastening said top over said base to provide a compact package, and a handle on said top by means of which the kit may be carried.

20 3. A prospector's kit comprising a hollow base, a top encasing said base, a curved material receiving sieve having openings therein and also having side portions adapted to rest upon said base, said tray having a closure at one end, a frame corresponding in length and breadth to said base and comprising transverse bars and longitudinal bars supported on said transverse bars, and with the latter alternately offset to provide a serpentine path between and around the ends of said transverse bars from one end of the base to the other, means for fastening said top over said base to provide a compact package, and a handle on said top by means of which the kit may be carried.

25 3. A prospector's kit comprising a hollow base, a top encasing said base, a curved material receiving sieve having openings therein and also having side portions adapted to rest upon said base, said tray having a closure at one end, a frame corresponding in length and breadth to said base and comprising transverse bars and longitudinal bars supported on said transverse bars, and with the latter alternately offset to

30 provide a serpentine path between and around the ends of said transverse bars from one end of the base to the other, said base having an opening at one end along its floor and portions extending inwardly from the sides and providing a central discharge way, means for fastening said top over said base to provide a compact package, and a handle on said top by means of which the kit may be carried.

35 4. A kit for separating minerals comprising a base structure having a bottom, two sides and an open end, and a connection for the upper portions of the sides at said open end inwardly extending raised portions at the open end of said base, a removable frame substantially corresponding in area to the area of said base, said frame having longitudinal and transverse riffle bars, certain of which are offset to provide a circuitous and unobstructed path along a substantial portion of said base, and a transversely

40 curved sieve corresponding substantially in length and width to the top of said base and having a closure for the end of said pan located adjacent the open end of the base.
